UNITED STATES PATENT OFFICE.

JACOB HOOK, OF RENO, NEVADA.

COVER FOR RADIATORS.

1,275,923.

Specification of Letters Patent. Patented Aug. 13, 1918

Application filed May 4, 1917. Serial No. 166,442.

To all whom it may concern:

Be it known that I, JACOB HOOK, a citizen of the United States of America, residing at Reno, in the county of Washoe and State 5 of Nevada, have invented certain new and useful Improvements in Covers for Radiators, of which the following is a specification, reference being had therein to the accompanying drawing.

10 10. This invention relates to covers for radiators and the like and has for its object the provision of a simple and efficient cover which may be easily supported upon and conveniently attached to the top of a hot 15 water, steam, or other similarly constructed radiator.

Another object of this invention is the provision of a simple and efficient cover which is so constructed as to collect dust, 20 soot and smoke and prevent the deposit of dust, soot and smoke discharged from the radiator upon the walls and ceiling of the room in which the radiator is positioned.

With these and other objects in view the 25 invention consists of certain novel combinations, constructions and arrangements of parts as will be hereinafter fully described and claimed.

In the drawings:—

30 Fig. 1 is an end view of the cover mounted upon a radiator;

Fig. 2 is a front view of the cover mounted upon a radiator, showing a shield thereon;

35 Fig. 3 is a section taken on the line 3—3 of Fig. 1;

Fig. 4 is a section taken on the line 4—4 of Fig. 2;

Fig. 5 is a detailed perspective of a shield 40 adapted to be mounted upon the cover;

Fig. 6 is a detailed perspective of a modified form of a shield which may be used in connection with the present invention.

By referring to the drawings it will be 45 seen that 1 designates the radiator which may be of any suitable size or construction and by carefully considering Figs. 1 and 2 it will be seen that a cover 2 is adapted to fit upon the top of the radiator 1 for the 50 purpose of collecting dust, soot and smoke which may be discharged from the radiator. This cover 2 comprises a pair of end plates 3 which end plates are provided with substantially arc-shaped grooves 4 punched 55 upon the inner face of the end plates 3 for

the purpose of receiving the substantially concavo-convex deflector plates 5, which deflector plates 5 have their respective ends seated in the sockets or channels 4 formed in the end plates 3. The ends of these plates 5 are soldered within the sockets 4 and thereby effectually hold the cover in an assembled position. By carefully considering Fig. 4 of the drawings it will be seen that the deflector plates 5 are alternately arranged 60 so as to have the respective side edges of one plate 5 fit within the channel portion of the adjoining channel plate. In other words these deflector plates 5 are arranged to substantially interlock for causing the dust or dirt which might ascend from the radiator to pass in an irregular passage through the cover and in this way settle on the plates. It of course should be understood that when 65 it is so desired this cover may be removed from the radiator for the purpose of emptying such accumulated matter which may be deposited upon the plates 5.

One of the end plates 3 of the cover is provided with an aperture 6 formed therein through which aperture 6 extends the pan 7. This pan 7 travels upon the supporting track-ways 8 which track-ways are provided with vertically extending flanges 9 for holding the pan 7 firmly upon the track-ways. These track-ways are provided with depending or forwardly extending end lips 10 which end lips are firmly soldered or otherwise secured to the inner face of the end plates 3 of the cover. A suitable handle 11 is carried by the pan 7 for the purpose of permitting the pan to be moved longitudinally upon the rails 8. It should be understood that the pan 7 is adapted to contain water for the purpose of moistening the atmosphere of the room within which the radiator is placed.

A detachable screen and protector 12 is fitted over the cover 3 and this shield or protector 12 is substantially U-shaped in cross section and comprises a metal body having an aperture 13 formed therein, which aperture is covered with wire mesh screening 14. A screen supporting plate 15 is secured around the edge of the aperture 13 and this plate 15 is substantially S-shaped in cross section. The plate 15 is secured to the outer face of the shield 12 and passes around the edge of the aperture 13 and is then bent backwardly upon itself for the 110

purpose of producing a screen receiving channel 14 within which the edges of the wire mesh screen 4 is firmly supported or otherwise secured. From the foregoing description it will be seen that a very simple and efficient means has been produced for the purpose of connecting or securing the wire mesh screen to the shield 12. The edges of the shield 12 are rolled and within the 10 rolled portion 16 thereof is mounted a reinforcing rod 17.

A modified form of the shield shown in Fig. 5 is illustrated in Fig. 6, wherein a shield comprising a body 18 is employed 15 having an overhanging end 19, which overhanging end is provided with an aperture 20. This aperture 20 is covered by means of a wire mesh screening 21 and the body of the shield 18 is extended downwardly to 20 produce an elongated portion 22 to fit against the wall and prevent the heat from the radiator from injuring the wall at the back of the radiator. This body 18 of the shield is also reinforced upon the edges 25 thereof in the same manner as that described with respect to the structure shown in Fig. 5 of the drawing. It should be understood that these shields shown in detail 30 or released from the cover of the radiator due to the fact that the same are formed of metal and will grip the radiator upon which the device is mounted in a spring like manner.

35 From the foregoing description it will be seen that a very simple and efficient cover has been produced for a radiator for the purpose of collecting dust, soot or other accumulation from a radiator and it should be 40 further understood that the hood may be very conveniently attached to or removed from the cover. Each of the deflector plates is provided with a plurality of laterally extending ears 23 which ears are formed adjacent 45 the edges of the deflector plates and are adapted to abut against the inner faces of the end plates 3.

What is claimed, is:—

1. A cover for a radiator comprising a body, said body comprising a pair of end plates, said end plates provided with a plurality of substantially arc shaped channels struck from the inner faces thereof, said channels arranged in staggered relation with respect to each other, and a plurality of deflector plates interposed between said end plates and having their ends seated within said channels of said end plates. 50

2. A cover for a radiator comprising a body, said body comprising a pair of end plates, said end plates provided with a plurality of substantially arc shaped channels struck from the inner faces thereof, said channels arranged in staggered relation with respect to each other, and a plurality of deflector plates interposed between said end plates and having their ends seated within said channels of said end plates, and a water pan supported upon said body. 60

3. A cover for a radiator comprising a body, said body comprising a plurality of end plates, substantially semi-cylindrical deflector plates interposed between said end plates and arranged in staggered relation with respect to each other, and a water containing pan carried by said body and positioned within said body and between said channel plates. 70

4. A cover for a radiator comprising a body, said body comprising a plurality of vertical end plates, deflector plates carried by said body, a plurality of horizontal tray supporting tracks carried by said body, each track comprising a vertically extending side flange and a horizontal flange, said horizontal flange provided with a depending vertical lip at each end thereof, said lips being secured to the inner faces of said end plates, and a water containing tray slidably mounted upon said tracks. 80

In testimony whereof I hereunto affix my signature.

JACOB HOOK.
